UNITED STATES PATENT OFFICE.

JOSEPH GRÜNINGER, OF NEW YORK, N. Y.

RECIPROCATING HYDRAULIC MOTOR.

SPECIFICATION forming part of Letters Patent No. 766,243, dated August 2, 1904.

Application filed October 5, 1903. Serial No. 175,822. (No model.)

To all whom it may concern:

Be it known that I, JOSEPH GRÜNINGER, a citizen of the United States of America, and a resident of the borough of the Bronx, New York 5 city, in the county and State of New York, have invented certain new and useful Improvements in Reciprocating Hydraulic Motors, of which the following is a specification.

My invention has reference to beer-pumps 10 of that type which are operated by water from city mains or other sources from which water is obtained under pressure. The novel pump which forms the subject-matter of this invention is characterized by being double-acting. 15 Air is compressed not only by the usual stroke of the piston and piston-rod, but also by the return stroke. For this reason two cylinders are provided, a water-cylinder and a separate air-cylinder, their pistons being connected to 20 the same piston-rod.

In the single-acting beer-pumps heretofore employed it sometimes happens that a water-discharge valve located within the apparatus does not work well. Under these circumstances 25 water is thrown upon the surface of the beer instead of air and that water mixes with the beer and spoils same. This cannot happen with my novel double-acting beer-pump, because a separate air-cylinder is provided into which water never flows. In places 30 doing a large business—say, for instance, during rush hours—two single-acting pumps are quite often employed. Two single-acting pumps certainly require a larger outlay of 35 capital than one double-acting pump, which latter does the same work as the two single-acting pumps.

The invention further consists in the construction of a novel water inlet and discharge 40 device and other details of construction, as well as the particular arrangement of various parts.

The invention is illustrated in the accompanying drawings, in which—

45 Figure 1 represents in front elevation a double-acting pump which embodies my invention, certain parts of the pump being

shown in section; and Fig. 2 is a section of detail on line *w-w* of Fig. 1.

Similar letters of reference denote like parts 50 in both figures.

The pump consists, essentially, of a hydraulic cylinder with water inlet and outlet pipes on both sides, an air-cylinder with air inlet and outlet pipes on both sides, and a novel 55 device for introducing into the hydraulic cylinder and discharging therefrom water automatically. This is done in such a manner that the water merely need be turned on for operating the pump, which then will work until 60 the water is turned off. By means of this novel device water is alternately and successively introduced into the hydraulic cylinder on both sides of the piston, whereby the pump is made double-acting with one single hydraulic cylinder. Likewise the air-cylinder is 65 made double-acting, the air-piston being secured to the same piston-rod which carries the hydraulic piston. Both pistons move simultaneously. By means of air inlet and discharge devices, one of which is secured to each 70 side of the air-cylinder, air is introduced into the air-cylinder, compressed therein, and discharged therefrom on both sides of the piston. By means of my novel construction 75 work is performed in the hydraulic cylinder as well as in the air-cylinder by the direct stroke of the piston as well as the return stroke.

In the drawings, *a* represents the hydraulic 80 cylinder, and *b* the piston. The air-cylinder is designated by the letter *c*, and *d* represents the air-piston. Both are mounted on a piston-rod *e*, which is common to both, and therefore both pistons are actuated simultaneously. 85 The water-inlet pipe *f* is connected to a tube *g*, which forms part of the automatic water inlet and outlet device. The tube *g* has two closed ends *g'* *g''*, which are conical in form. Near each of the closed ends the tube *g* has 90 several openings *g'''* *g''''*. Usually four are provided. At each end of the tube *g* there is a stuffing-box *h* *h'*, in which the tube moves to and fro. The stuffing-box *h* is provided with

packing h^2 , consisting of lamp-wick or other suitable material. Likewise the stuffing-box h' has similar packing h^3 . At the end of each stuffing-box there is a conical opening, into which fits a conical closed end of the movable tube. Each conical opening at the end of a stuffing-box forms a valve with a conical closed end of the movable tube, which closes off tightly the water when the conical closed end of the tube is located in the conical opening of the end of the stuffing-box. Opposite the closed end of the tube g a water-discharge pipe f' is provided, and another discharge-pipe, f^2 , is secured in like manner to the stuffing-box h' . Both are united below and form a single pipe f^3 , which leads into the waste or sewer pipes. At the end of the stuffing-box h there is a water-conducting tube i , while a similar tube i' is secured at the end of the stuffing-box h' . There are provided on the tube g two collars h, h' , which are permanently connected thereto near the water-inlet tube f . The collar h carries a pin l , while the collar h' carries a pin l' . The tube g , with the stuffing-boxes, openings, and pipes, represents a valve system. An automatic device is provided for moving the tube g by means of the pins secured thereto. This device consists of a metal bar m , which is pivoted upon a pin projecting from a post o . The metal bar carries near its top a weight w . The bar m , with weight w , is actuated by the pins p, p' , permanently secured on the piston-rod e by means of two collars p^2, p^3 . The collars extend above into two sliding rings p^4, p^5 , which are supported by a guiding-rod g . This rod is permanently secured above the piston-rod between the two cylinders. The pins p, p' being permanently secured to the piston-rod will move with same, while the steadyng-rings p^4, p^5 will slide along the guiding-rod g .

The water-pipe i , leading from the stuffing-box h , connects with the hydraulic cylinder, so that the water enters on the side where the piston-rod passes into same. The water-pipe i' , however, leads to the opposite end of the hydraulic cylinder and feeds water into same in the opposite direction. From this it is apparent that water is fed into the hydraulic cylinder on both sides of the piston. This is done alternately and successively, so that the piston is moved forward and backward and in accordance therewith the piston 55 in the air-cylinder.

The double-acting pump has been described as being operated by water, but may also be operated by steam.

The air-cylinder has an air inlet and discharge tube r on one side and an air inlet and discharge pipe r' on the opposite side. The pipe r is connected to an automatic air inlet and discharge valve s , while the pipe r' has a

similar valve s' . From these valves the pipes r^2, r^3 conduct the air into the pipe r^4 , which 65 connects with both, and from there the air is forced into the air-reservoir.

Assuming that the pipe g of the automatic-operating device and the pistons in the cylinders are in the position indicated in the drawings, then the water entering through the pipe f will fill the movable pipe g . The openings g^4 are then located within the packing h^3 of the stuffing-box h' , and no water will pass through the tube i' . In the position shown 75 in the drawings the closed end g^2 closes off the discharge-tube f' , and the openings g^3 in the tube g are located right below the tube i . Therefore the water will flow through the holes g^3 and the tube i into the hydraulic cylinder and push the piston b forward. While this takes place the pin p' on the piston-rod e will reach the metal bar m , which is loosely secured, and move same without changing the location of the tube g until the weight w passes 80 the vertical center line. At this moment the weight w enters into action and in falling down moves the bar m , whose lower end strikes against the pin l' , whereby the tube g will be moved to the right. In this new position of 85 the tube g its closed end g^2 closes off the discharge-pipe f^2 , and the openings g^4 are right below the tube i' and establish connection therewith, while the openings g^3 at the other end of the tube will move into the packing h^2 and communication between the tube i and the openings g^3 is interrupted. The water flowing now into the tube g will pass through the openings g^4 and the pipe i' into the hydraulic cylinder, entering there from 90 the opposite side, and therefore pushing the piston backward. The returning piston now forces the water first introduced in the cylinder out of same through the same pipe i , through which it was introduced. The water 95 then flows through the pipe i , the opening g^5 , and the discharge-pipe f' into the waste or sewer pipe. While this takes place the metal bar m is moved by the pin p . Upon passing the vertical center line the weight w on the 100 bar m enters into action, and in falling down the lower end of the bar m strikes the pin l , whereby the latter is shifted into its original position. (Shown in the drawings.) The water flowing now into the tube g will again 105 flow through the openings g^3 and the tube i into the cylinder and move the piston forward again. The advancing piston then forces the water contained in the cylinder out of same. The water returns through the pipe i' , passing 110 through the opening g^6 of the stuffing-box h' , and flows through the discharge-pipe f^2 into the sewer-pipes.

The action of the air-cylinder is the same as the action of the hydraulic cylinder, because 115 the pistons are united to one piston-rod and

move simultaneously. When the pistons occupy the positions shown in the drawings, then the air contained in the air-cylinder will be compressed and forced through the pipes r , r^2 , 5 and r^4 into the reservoir. Meanwhile the space on the other side of the air-piston has been filled with air by means of the automatic inlet-valves, and upon return of the piston this air is compressed and discharged through the 10 pipes r' , r^3 , and r^4 into the reservoir.

Having thus described my invention, I claim as new and desire to secure by Letters Patent—

1. In a water-actuated double-acting pump, a water inlet and discharge device comprising 15 a movable tube having conical and closed ends adapted to act as valves, a water-supply tube secured to its center portion, a stuffing-box with packing at each end of the movable tube, a conical opening at the end of each stuffing- 20 box forming a valve-seat for each conical closed end of the movable tube, a water-conducting pipe secured to each stuffing-box, openings in the movable tube near the closed ends adapted to establish communication with 25 the water-conducting pipes, two collars fixed to the movable tube, a pin secured to each collar, and means for automatically shifting the tube to and fro during the operation of the 30 pump whereby communication is alternately established between the movable tube and the water-conducting pipes.

2. A water-actuated double-acting pump comprising a hydraulic cylinder with piston, an air-cylinder with piston, a piston-rod common to both cylinders having two collars with pins permanently secured to its middle portion, in combination with an automatic water inlet and discharge device consisting of a movable tube having conical closed ends adapted 40 to act as valves, a water-supply tube secured to its center portion, a stuffing-box with packing at each end of the movable tube, a conical opening at the end of each stuffing-box forming a valve-seat for each conical closed end of the movable tube, 45 a water-conducting pipe secured to each stuffing-box, holes in said movable tube near the closed ends adapted to establish communication alternately with the water-conducting pipes, a metal bar with adjustable weight at 50 its top portion pivoted upon a pin projecting from a post mounted so that its lower end actuates the movable tube, and means for moving the metal bar to and fro during the operation of the pump.

3. A water-actuated double-acting pump comprising a hydraulic cylinder with piston, an air-cylinder with piston, a piston-rod common to both cylinders having two collars with pins permanently secured to its middle portion, in combination with an automatic water inlet and discharge device consisting of a mov-

able tube having conical closed ends adapted to act as valves, a water-supply tube secured 65 to its center portion, a stuffing-box with packing at each end of the movable tube, a conical opening at the end of each stuffing-box forming a valve-seat for each closed conical end of the movable tube, a water-conducting pipe 70 connecting one stuffing-box with the hydraulic cylinder on that side where the piston-rod enters, a water-conducting pipe connecting the other stuffing-box with the hydraulic cylinder on the opposite side, holes in the movable 75 tube near the closed ends of same adapted to establish communication alternately with the water-conducting pipes, two collars with pins fixed to the movable tube, a metal bar with weight at its top pivoted upon a pin projecting from a post in such a manner that its middle portion is moved by the pins on the piston-rod and its bottom end strikes the pins on the movable tube thereby shifting same during the operation of the pump. 85

4. In a water-actuated double-acting beer-pump, a water inlet and discharge device comprising a movable tube having conical closed ends adapted to act as valves, a water-supply tube secured to its center portion, two collars 90 with pins on the movable tube in its center portion, a stuffing-box with packing at each end of said tube, a conical opening at the end of each stuffing-box forming a valve-seat for each closed conical end of the movable tube, 95 a water-conducting pipe secured to each stuffing-box, holes in said movable tube near the closed ends adapted to establish communication alternately with the water-conducting pipes, a metal bar with adjustable weight at 100 its top portion pivoted upon a pin projecting from a post mounted so that its lower end actuates the movable tube, and means for moving the metal bar to and fro during the operation of the pump. 105

5. In a water-actuated double-acting beer-pump, a movable tube closed at its ends, a water-supply tube attached to its center portion, two collars permanently fixed to the middle portion of the movable tube, a pin on each collar, holes in the movable tube near the closed ends, means for allowing the water to pass alternately through the openings in the movable tube, and means for shifting said tube to and fro during the operation of the 115 pump.

6. A water-actuated double-acting beer-pump comprising a hydraulic cylinder with piston, a pipe secured thereto on each end, in combination with an automatic water inlet and discharge device consisting of a movable tube having conical closed ends, a water-supply tube secured to its center, two collars with pins in the middle portion of said movable tube, a stuffing-box with packing at each end 120 of said tube, a conical opening at the end of

each stuffing-box forming a valve-seat for each conical closed end of the movable tube, holes in the movable tube near its closed ends adapted to establish communication alternately between the stuffing-box and the hydraulic cylinder, a metal bar with weight at its top pivoted upon a pin projecting from a post mounted so that its lower end actuates the pins on the movable tube, two collars with pins per-

manently fixed to the piston-rod mounted so ¹⁰ that same actuate the metal bar when the piston-rod moves.

Signed at New York, N. Y., this 12th day of September, 1903.

JOSEPH GRÜNINGER.
